YARN CARRIER

Edward Jentsch, Clifton, N. J.

Application November 4, 1948, Serial No. 58,266

7 Claims. (CL 66—126)

1

The present invention relates to a yarn carrier and relates more particularly to a yarn carrier having parts that are replaceable and adjustable.

An object of my invention is to provide a yarn carrier in which various parts that are subject to wear or may be damaged may be replaced without discarding the entire carrier. Another object of my invention is to provide a yarn carrier that may easily be adjusted for proper operation in relation to a knitting machine after any part of the carrier has been replaced. Further objects and advantages of my invention will be apparent and best understood from the following description and the accompanying drawings in which:

Fig. 1 is a perspective view of a yarn carrier embodying my invention;

Fig. 2 is a front view of the yarn carrier illustrated in Fig. 1;

Fig. 3 is a side view of the yarn carrier illustrated in Fig. 1;

Fig. 4 is a rear view of the yarn carrier illustrated in Fig. 1; and

Fig. 5 is a side view of part of the yarn carrier illustrated in Fig. 1.

Referring now to the drawings in detail, there is a yarn carrier designated generally by the numeral 1. The carrier 1 includes a main body portion 2 in the form of an angle member. A nose or tube holding portion 3 is adjustably supported at the lower end of the main body member 2 and may be adjusted lengthwise of the main body member 2 so that its end may be readily located at a desired position relative to a knitting machine.

The top of the main body member 2 is T-shaped and has slotted openings 4 in the arms of the T to receive studs 5 that secure the carrier to the knitting machine. A thread guide 6 of wear resisting material, such as hardened steel, is removably supported at the top of the T-shaped portion of the main body portion 2 by a plate 7. The plate 7 is also held in place by the studs 5 and the center portion of the plate 7 may be raised to receive the end of the guide 6 between the plate 7 and the top of the main body portion 2. The end of the guide 6 may be bent as indicated at 8 in Fig. 5 to provide a spring action that removably holds the guide 6 in place and provides a spring action so that the guide 6 can serve as a washer to hold the studs 5 against loosening.

The lower portion of the main body 2 of the carrier extends downwardly at an angle to the T-shaped top portion and this downwardly extending portion may be arched or curved. The lower end of the downwardly extending portion of the main body 2 is slotted as indicated at 9 and a fastening device or bolt 10 extends through the slot 9. The bolt 10 is threaded to the nose or tube holding member 3 and the head of the bolt 10 engages with a clamping member 11 with the nose portion 3 and the clamping member 11

2

being located on opposite sides of the main body 2.

The main body 2 has recessed portions on its underside that extend around the slot 9 and these recessed portions are shaped to fit the upper end of the nose portion 3 with a sliding fit so as to hold the nose portion 3 in proper alignment with the main body of the carrier. In addition the clamping member or bracket 11 may also be provided with lips 11a that extend over and engage with the side edges of the main body portion 2 of the carrier so that the clamping bracket 11 will not turn when it is tightened. Thus, when the bolt 10 is tightened the nose portion 3 of the carrier is secured in proper alignment to the main body portion 2 of the carrier. When the bolt 10 is loosened, the nose portion 3 may be moved lengthwise of the main body portion 2 without disturbing its alignment in the carrier so as to adjust the position of the end of the nose portion 3 relative to the knitting machine or the nose portion 3 may be removed entirely from the carrier so that it may be replaced.

25 The nose or tube holding member 3 extends downwardly from the main body 2 of the carrier and it may be of the construction in which a pair of opposed spring-jaws 12 and 13 are located at the lower end thereof and engage with and hold a thread-guide tube 14 in place between them. The jaws 12 and 13 may also have apertures 15 and 16 to receive a carrier-tube releaser (not shown) for releasing the tube 14 from the jaws. Such a construction is more fully described and shown in my copending application, Serial No. 58,265 filed November 4, 1948, and reference may be made thereto in regard to such details.

40 In operation, a thread 17, as shown in Figs. 2-4, passes through an opening 18 in the removable thread guide 6 and then through an opening 19 in the main body portion of the carrier. The thread 17 then runs along the underside of the carrier and over a roller 20 to an opening 21 in the tube holder 3. From the opening 21, the thread 17 passes through a groove 22 to the top of the tube 14 and then through the tube 14.

45 The roller 20 over which the thread 17 passes on the back of the main body 2 of the carrier is of hardened steel or other suitable wear resistant material and it contacts with and supports the thread 17 in a position spaced from the main body of the carrier so that the frictional drag on the thread is reduced to a minimum. The guide roller 20 may be removably supported on the main body 2 of the carrier by a wire clip 23 that is held in place on the carrier by a screw 24. Thus, the roller 20 may be removed and replaced readily if it becomes worn or damaged.

55 As will be seen from the drawings, the thread

17 contacts the carrier at only three points and the frictional drag on the thread is thus reduced so that the thread may be guided more easily and accurately by the carrier and with reduced breakage. In addition, wear on the carrier itself is reduced by the removable guides of wear resistant material and the life of the carrier is greatly increased. In addition, other portions of the carrier are adjustable and may be replaced without discarding the entire carrier if they become worn or damaged.

It will be understood that various changes and modifications in the embodiment of the invention as illustrated and described herein may be made by those skilled in the art without departing from the scope of the invention as defined by the following claims.

I claim:

1. A yarn carrier which includes a main body portion having a slotted opening at one end thereof, a nose portion extending from the slotted end of said main body portion, said main body portion having recessed portions adjacent the slotted opening therein, said recessed portions being shaped to fit said nose portion with a sliding fit, a clamping member located on said main body portion in opposed relation to said nose portion, said clamping member having flanges along its sides that extend over and engage with the side edges of said main body portion and fastening means engaging with said nose portion and said clamping member and extending through the slotted opening in the main body portion, said fastening means removably securing said nose portion to said main body portion and permitting lengthwise movement of the nose portion relative to the main body portion.

2. A yarn guide as defined in claim 1 which includes a thread supporting member of wear resistant material removably secured to the main body portion, said thread supporting member being engaged by and supporting a thread in a spaced relation to the surface of the main body of the carrier.

3. A yarn carrier which includes a main body portion having a slotted opening at one end thereof, a nose portion extending from the slotted end of said main body portion, a clamping member, said clamping member including a plate engaging with one side of the main body and flanges at the edges of said plate engaging with the side edges of the main body portion, said nose portion and said clamping member being located on opposite sides of said main body portion and fastening means engaging with and removably securing said clamping member and said nose portion to said main body portion, said fastening means extending through said slotted opening and permitting adjustment of said nose portion lengthwise of the main body portion.

4. A yarn carrier which includes a main body portion having a slotted opening at one end thereof, a nose portion extending from the slotted end of said main body portion, said main body portion having recesses in one face thereof adjacent the slotted opening therein, said recesses being shaped to receive one end of the nose portion with a sliding fit, a clamping member, said nose portion and said clamping member being located on opposite sides of said main body portion and fastening means engaging with and removably securing said clamping member and said nose portion to said main body portion, said fastening means extending through said slotted opening

opening and permitting adjustment of said nose portion lengthwise of the main body portion.

5. A yarn carrier which includes a main body portion, said main body portion having a top and a bottom section disposed in angular relation to each other and having a slotted opening in said bottom section, a nose portion extending from said bottom section, a clamping member, flanges carried by said clamping member, said flanges extending over and engaging with the side edges of the bottom section of the main body portion, said clamping member and said nose portion being located on opposite sides of said bottom section and fastening means engaging with said clamping member and said nose portion and extending through the slotted opening in the bottom section of the main body portion, said fastening means removably securing said nose portion to the main body portion and permitting adjustment of the nose portion lengthwise of the main body portion.

6. A yarn carrier which includes a main body portion, said main body portion having a top and a bottom section disposed in angular relation to each other and having a slotted opening in said bottom section, a nose portion extending from said bottom section, said bottom section of the main body portion having recesses in one face thereof adjacent the slotted opening therein, said recesses being shaped to receive one end of the nose portion therein with a sliding fit, a clamping member, said clamping member and said nose portion being located on opposite sides of said bottom section and fastening means engaging with said clamping member and said nose portion and extending through the slotted opening in the bottom section of the main body portion, said fastening means removably securing said nose portion to the main body portion and permitting adjustment of the nose portion lengthwise of the main body portion.

7. A yarn carrier which includes a main body portion, said main body portion having a top and a bottom section disposed in angular relation to each other and having a slotted opening in said bottom section, a nose portion extending from said bottom section, said bottom section of the main body portion having recesses in one face thereof adjacent the slotted opening therein, said recesses being shaped to receive one end of the nose portion therein with a sliding fit, a clamping member, flanges carried by said clamping member, said flanges extending over and engaging with the side edges of the main body portion, said clamping member and said nose portion being located on opposite sides of said bottom section and fastening means engaging with said clamping member and said nose portion and extending through the slotted opening in the bottom section of the main body portion, said fastening means removably securing said nose portion to the main body portion and permitting adjustment of the nose portion lengthwise of the main body portion.
